POCKET CLIP FOR A WRITING INSTRUMENT OR SIMILAR ARTICLE

Robert John Darst, Fort Madison, Iowa, assignor to Textron Inc., Providence, R.I., a corporation of Rhode Island

Filed Apr. 18, 1966, Ser. No. 1,926

Term of patent 14 years

(Cl. D74—2)

FIG. 1 is a front elevational view of a pocket clip for a writing instrument or similar article showing my new design, the broken line illustration of the cap being for illustrative purposes only;

FIG. 2 is a side elevational view thereof;

FIG. 3 is a bottom plan view of the view in FIG. 2; and

FIG. 4 is a top plan view thereof.

I claim:

The ornamental design for a pocket clip for a writing instrument or similar article, substantially as shown and described.
